UNITED STATES PATENT OFFICE

94,094

DESIGN FOR A COMBINED TRAY, BREAD KNIFE, AND HOLDER

James Stanley Ness, Chicago, Ill., assignor to Waters-Genter Company, Minneapolis, Minn., a corporation of Minnesota

Application June 4, 1934, Serial No. 52,058

Term of patent 3½ years

To all whom it may concern:

Be it known that I, James Stanley Ness, a citizen of the United States, residing at Chicago, in the county of Cook and State of Illinois, have invented a new, original, and ornamental Design for a Combined Tray, Bread Knife, and Holder, of which the following is a specification, reference being had to the accompanying drawing, forming part thereof.

The figure is a perspective view of the article, showing my new design.

I claim:

The ornamental design for a combined tray, bread knife, and holder as shown.

JAMES STANLEY NESS.
